UNITED STATES PATENT OFFICE.

JOHN J. GRANT, OF GREENFIELD, MASSACHUSETTS, ASSIGNOR TO HIMSELF, S. L. WILEY, AND CHARLES P. RUSSELL, OF SAME PLACE.

IMPROVEMENT IN SCREW-CUTTING MACHINES.

Specification forming part of Letters Patent No. 133,026, dated November 12, 1872.

To all whom it may concern:

Be it known that I, JOHN JAMES GRANT, of Greenfield, in the county of Franklin and State of Massachusetts, have invented an Improved Machine for Drilling and Cutting Screw-Threads; and the following description, taken in connection with the accompanying plate of drawing hereinafter referred to, forms a full and exact specification, wherein are set forth the nature and principles of the invention, by which the same may be distinguished from others of a similar class, together with such parts thereof as are claimed as new and are desired to be secured by Letters Patent of the United States.

My invention relates to that class of machines which are made use of for drilling and for cutting screw-threads on bolts and nuts; and the [nature thereof consists, first, in the mechanism made use of for adjusting the dies and holding the same firmly in position, hereinafter shown and described. Second, in the apparatus used for operating the head-stock and pressing the same toward the shaft in order to cause the dies to grip a bolt to be screwed on the tap to take hold of a nut, in which it is required to have a thread cut, as hereinafter specified. Third, in combining with the disk a reversible chuck-plate, so constructed as to hold nuts of different sizes and shapes, and bring either thereof in position to be operated on with facility. Fourth, in the combination of parts constituting the mechanism, whereby the operator is enabled to adjust the feed in such a manner as to make it light or heavy, as may be required. Fifth, in combining with the feeding mechanism a yoke provided with sleeves, a work-holding chuck provided with a bevel-gear, and a bevel-gear in such a manner that the feed is operated by the same power which revolves the shaft, and the operating gear is placed at the side of the machine.

In the accompanying plate of drawing, which illustrates my invention and forms a part of the specification thereof, corresponding parts are illustrated by similar letters.

Figure 1 is a view in perspective of a machine with my improvements applied thereto.

Fig. 2 is a plan of the same. Fig. 3 is a view of the starting-lever, illustrating the same in detail. Fig. 4 represents the die-holding disk. Fig. 5 is an end view of the machine illustrating the feed mechanism. Figs. 6, 7, and 8 are views in detail of the nut-chuck. Figs. 9, 10, and 11 illustrate, in detail, parts of the feed mechanism.

The construction, operation, and relative arrangement of the component parts of my machine are as follows: The head-stock B, resting upon the shears A of the machine, supports and constitutes the bearing of the tubular journal or disk shaft, upon which the die-holding disk D can be rotated. The said disk, as will be clearly seen by reference to the drawing, is placed in an eccentric relation with the working center of the tool or work-holding chuck F, carried by the tubular shaft H, and is provided with a proper number of circular apertures, which may be used either as openings for the drill to pass through when work is placed upon the face of the disk, to hold different-sized dies d d', or support the nut-holding chuck J. The eccentric position occupied by the said disk allows of its being so rotated as to bring the center of any one of the said apertures in line with the axis of the shaft H, thereby enabling the operator to accurately adjust any one of the several dies, or the nut-holding chuck into working position opposite the tool or work-holding chuck F. The said disk may be locked firmly in position after being thus adjusted by means of the pin k, which passes through an aperture cut for its reception in the projection l, cast upon the head-stock and fits accurately in either of the cylindrical slots m. The pin is held in position by the dog or clutch n, provided with a claw, o, so constructed as to fit exactly within an annular slot cut upon the said pin. The dies d for cutting screw-threads are described and claimed in the specification forming part of Letters Patent No. 120,266, granted to me on the 24th day of October, 1871, and are combined with the said disk in substantially the manner specified in the said patent for fitting them to the die-stock. For this pur-

pose the said disk is provided with an annular cavity with female screws for the reception of the set-screws p , which, together with the set-screws r , operated upon the circumference of the disk, may be screwed up to hold the dies in any position to which they are adjusted. By means of the starting-lever S the head-stock B is pressed up toward the work-holding chuck F , in order to bring the die against the end of the bolt to be screwed, and it is held there until the thread begins to take hold and the work feeds itself. The said lever works upon a fixed fulcrum or bolt attached to the head-stock, and is provided with a shoulder, s^1 , by means of which it is supported in position when at rest. A pawl, s^2 , is pivoted to the end of the lever, which catches in the rack upon the shears of the machine when the handle is raised, and causes the head-stock to move forward; but when the handle is allowed to fall the stud s^3 engages with the pawl and causes it to rise and disengage itself entirely from the rack in such a manner as to allow the head-stock to be moved in either direction with equal facility, or admit of its being entirely removed from the bed of the machine. The nut-holding chuck J is secured in a socket, T , provided with a tubular projection, t^1 , which fits accurately in a circular aperture, t^2 , prepared for its reception in the disk D , where it is secured in position by a set-screw. One side of the said chuck is provided with a series of hexagonal receptacles of different sizes, while the opposite side is furnished with cavities square in form, in order that the implement may be adapted to nuts of various shapes and sizes. Either side of the said chuck may be used with equal facility by merely reversing the position of the same in the socket, and it is held in any desired position by means of the vertical spring-bolt v^1 , which fits accurately in the cylindrical slot v^2 . As some metals can be pieced with much greater rapidity and facility than others, the machine is provided with an adjustable feed mechanism, whose motion is perfectly regular and even. For this purpose one end of the tubular shaft H , upon which revolves the tool-holding chuck F , is provided with two or more cams, h^1 h^2 , one or all of which may be made to engage with the reciprocating-bar w , as the operator may prefer, by properly adjusting the casing w^1 , in which the said reciprocating-bar is secured by means of the milled set-screw w^2 , which works in an elongated slot, w^3 , cut in the said casing, and is screwed into a bracket attached to the yoke x . The reciprocating-bar w is kept in contact with the cam or cams by means of the spiral spring w^4 , and the length of its vibrations may be accurately adjusted by the thumb-nut w^5 . It is provided with a pawl, w^6 , which engages with the ratchet-wheel y . The screw-shaft y' passes through a cylindrical aperture

in the yoke x , which constitutes a bearing for the same, and engages with a female thread cut for its reception in the standard z . By this construction the traversing motion of the said yoke which regulates the feed may be accurately adjusted—that is to say, when the reciprocating-bar is made to engage with a single cam the pawl catches in the teeth of the ratchet-wheel and turns the same a certain distance at one revolution of the mandrel. If the said bar engages with two of the cams the wheel travels over the same distance at each half a revolution; and if three cams are used, at each third of a revolution, and so on. The extent of the movement of the reciprocating-bar is adjusted by the thumb-nut w^5 . The sleeves x' of the yoke x clasp the tubular shaft H in such a manner as to impart longitudinal travel or feed to the work-holding chuck F upon the end thereof when the said yoke is moved by the ratchet-wheel. Both rotary motion and horizontal travel are imparted to the work-holding chuck F by the bevel-gear F^1 , which engages with bevel-gear F^2 of the said chuck. The tubular shaft of the bevel-gear F^1 revolves upon a fixed journal rigidly attached to the said yoke, and is operated as may be desirable.

This arrangement of the operating-gear is very advantageous and convenient, as the operator is brought near his work, and long bolts, which are passed through the tubular shaft H , are not in the way of the turning of the crank.

Having thus described the construction and operation of my invention, I will indicate in the following clauses what I claim and desire to secure by Letters Patent of the United States—

1. In a machine for drilling and cutting screw-threads, the apparatus made use of for adjusting the dies and holding the same firmly in position, consisting of the die-holding disk D provided with cylindrical slots m , the pin k upon which is cut an annular slot, the projection l cast solid with the head-stock B and provided with a cylindrical aperture, and the dog n pivoted to the head-stock B , and provided with a claw, o , all combined and operating together, as and for the purposes described.

2. The apparatus used for operating the head-stock B , consisting of the lever S provided with the shoulder s^1 and stud s^3 , the pawl s^2 pivoted to the end of said lever, and the rack attached to the shears A , when combined and operating together, as described.

3. The combination of the disk D , the reversible chuck-plate J , constructed as described, the socket in which the said chuck-plate is fitted, and the vertical spring-bolt, all constructed and arranged as described.

4. The combination of the shaft H provided with two or more cams, h^1 h^2 , reciprocating-bar

w, adjustable casing *w*¹ having a slot, *m*³, spiral spring *w*⁴, thumb-nut *w*⁵, pawl *w*⁶, and the ratchet-wheel *y*, substantially as and for the purpose set forth.

5. In combination with the feeding mechanism which forms the subject-matter of the preceding claim, the yoke *x* provided with sleeve *x*', the work-holding chuck *F* provided with a bevel-gear, *F*¹, and the bevel-gear *F*², all operating together, as described.

In testimony that I claim the foregoing I have hereunto set my hand and seal this 3d day of July, 1872.

JOHN J. GRANT. [L. S.]
